(57) **CLAIM**

The ornamental design for an insert for an insect trapping device, as shown and described.

DESCRIPTION

FIG. 1 is a perspective view of an insert for an insect trapping device embodying our new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is bottom view thereof.

The oblique shade lines in the drawings depict a surface that is translucent.
